US00D936666S

(12) **United States Design Patent** (10) **Patent No.:** **US D936,666 S**
(45) **Date of Patent:** **** Nov. 23, 2021**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Freddy Anzures**, San Francisco, CA (US); **Greg Apodaca**, Mountain View, CA (US); **Ismael Basso**, San Francisco, CA (US); **Imran Chaudhri**, San Francisco, CA (US); **Jonathan P. Ive**, San Francisco, CA (US); **Chanaka Karunamuni**, Cupertino, CA (US); **Joe Marianek**, New York, NY (US); **Matthew Dean Rohrbach**, San Francisco, CA (US); **Jeremiah Daniel Shaw**, San Francisco, CA (US); **Christopher I. Wilson**, San Francisco, CA (US)

(73) Assignee: **Apple Inc.**, Cupertino, CA (US)

(**) Term: **15 Years**

(21) Appl. No.: **29/691,715**

(22) Filed: **May 17, 2019**

Related U.S. Application Data

(63) Continuation of application No. 29/655,621, filed on Jul. 5, 2018, now Pat. No. Des. 849,026, which is a continuation of application No. 29/619,456, filed on Sep. 29, 2017, now Pat. No. Des. 822,713, which is a continuation of application No. 29/563,422, filed on May 4, 2016, now abandoned, which is a continuation of application No. 29/523,055, filed on Apr. 6, 2015, now Pat. No. Des. 756,396, which is a continuation of application No. 29/457,315, filed on Jun. 9, 2013, now Pat. No. Des. 726,219.

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outermost dash-dash broken lines in the FIGURE show a display screen or portion thereof, and form no part of the claimed design. The other dash-dash broken lines in the FIGURE show portions of the graphical user interface that form no part of the claimed design. The dot-dash broken lines in the FIGURE, and the areas within the dot-dash broken lines, form no part of the claimed design.
